SPOOL.

1,074,786.

Specification of Letters Patent. Patented Oct. 7, 1913.

Application filed January 23, 1913. Serial No. 743,753.

To all whom it may concern:

Be it known that we, Alois Glaser and John W. Edson, citizens of the United States, residing, respectively, at Dedham, in the county of Norfolk, and Hingham, in the county of Plymouth and State of Massachusetts, have invented certain new and useful Improvements in Spools; and we do hereby declare the following to be a full, clear, and exact description of the invention, such as will enable others skilled in the art to which it appertains to make and use the same.

The invention relates to thread spools of the type in which the spool heads are provided with inclined or conical thread bearing surfaces, and its object is to provide a light and inexpensive spool which possesses great strength and durability.

To this end the invention consists of the features of construction and combinations of parts hereinafter described and claimed.

The invention will be readily understood from an inspection of the accompanying drawings and the following detailed description of the spool illustrated therein.

In the drawings, Figure 1 is a central longitudinal section through a thread spool embodying the invention in its preferred form, and Fig. 2 is an end view of the spool.

As shown the spool is provided with a central tube 1 which may be conveniently manufactured from paper, fiber or analogous material. Surrounding the tube 1 is the cylindrical barrel 2 and the inclined head 3 which are formed integral with the barrel. The barrel and integrally connected heads are formed by molding about the tube 1 a compound which, when it hardens, presents a smooth and unyielding surface for supporting the thread wound upon the spool. By forming the barrel and heads of the spool from molded material true and accurate thread engaging surfaces are provided which are unbroken by joints which are liable to open or work loose under atmospheric changes and variations in temperature, and into which the thread is liable to be drawn in winding it upon the spool, especially when wound under comparatively heavy tension.

In order that the spool may be as light as practicable, the heads 3 are molded in the form of comparatively thin conical

flanges extending from the ends of the barrel portion 2 of the spool. These end flanges are subjected to heavy pressure when the thread is wound upon the spool, especially when it is wound under comparatively heavy tension, and to support and strengthen the heads so that they may effectively withstand such pressure, end disks 4 are fitted within the head flanges. These disks not only strengthen and support the heads against the pressure to which they are subjected, but also furnish flat plain surfaces at the ends of the spool and close the cavities which would otherwise be present, owing to the shape of the head flanges 3. The end disks 4 may be conveniently formed of fiber, hardened paper board or other suitable material.

The ends of the inner tube 1 project beyond the barrel portion 2 of the spool, and are arranged to abut against the inner surface of the heads 4. The heads are secured in position at the ends of the spool by securing plugs 5 which fit within the tube 1 and are provided with conical flanges 6 fitting within similar holes in the heads 4 and retaining them against the ends of the tube 1 and the inner surface of the head flanges 3. As shown, the plugs comprise hardened paper or fiber tubes 7 within which are composition cores 8 molded within the tubes, and provided at their centers with cylindrical bearing surfaces 9 for supporting the spool. The plugs are cemented or otherwise secured to the inner surface of the tube 1 and to the end disks 4.

While it is preferred to employ the specific construction and arrangement of parts shown and described, it will be understood that this construction and arrangement is not essential except so far as set forth in the claims, and may be varied and modified without departing from the broader features of the invention.

Having explained the nature and object of the invention, and specifically described one form of spool in which it may be embodied, what is claimed is:

1. A thread spool comprising an inner tube, a barrel and conical head flanges surrounding the tube, end disks fitting within the head flanges, and plugs securing the disks to the ends of the inner tube.

2. A thread spool comprising an inner tube, a molded barrel and integral conical

head flanges surrounding the tube, end disks, and devices securing the end disks to the inner tube.

3. A thread spool comprising a tube 1, a molded barrel 2 surrounding the tube and provided with head flanges 3, end disks 4 fitting within the flanges, and plugs 5 se-

curing the end disks to the ends of the tube 1.

ALOIS GLASER,
JOHN W. EDSON,
